UNITED STATES PATENT OFFICE.

MAX EISENSCHIML, OF ASCH, CZECHOSLOVAKIA.

DRIVING MECHANISM FOR STRAIGHT-KNITTING MACHINES.

Application filed April 26, 1923. Serial No. 634,911.

To all whom it may concern:

Be it known that I, MAX EISENSCHIML, a citizen of the Republic of Czechoslovakia, and resident of Asch, Czechoslovakia, have 5 invented certain new and useful Improvements in Driving Mechanism for Straight-Knitting Machines, of which the following is a specification.

My present invention relates to a driving 10 mechanism for straight knitting machines and has for its object to convert a hand driven knitting machine of such kind into a motor driven machine, at the same time to enable the said mechanism to be applied to 15 a machine of such kind without difficulty, whether the machine is mounted on a frame or stand or on a table, and to adapt the apparatus operating the carriage of the machine to any stroke i. e. to any width of the 20 straight knitting machine.

For such purpose the unitary driving mechanism comprising an element adapted to stop the machine not only after a predetermined number of revolutions of the driving 25 shaft but also in the event that the knitting thread breaks or exhausts, is combined with an endless member preferably a chain operated by the said driving shaft, means being provided adapted to be reciprocated by the endless member and further 30 means, whereby the carriage of the knitting machine will be engaged by the first named means and disengaged from the same.

Another feature of the invention consists in the provision of means to adjust the second named means according to the stroke 35 of the carriage of the knitting machine.

Referring to the accompanying drawings forming a part of this specification Fig. 1 40 is a side elevation of the unitary driving mechanism and Fig. 2 is an elevation partly in section. Fig. 3 is a front elevation of the chain gear. Fig. 4 a plan view of the same. Fig. 5 is a cross section and Fig. 6 is a de- 45 tail elevation partly in section.

The frame 1 of the additional unitary mechanism is secured as shown at 2 to the supporting frame 3 of the well known straight knitting machine, which being here- 50 tofore driven by hand is now converted into a motor driven machine. The frame 1 supports in suitable bearings 4 the driving shaft 5, on which is loosely mounted a driving pulley 6 which may be driven by a belt or 55 the like from a source of power not shown. The hub 8 of the pulley 6 forms the right

hand or fixed portion of an ordinary claw left hand or a clutch, the movable portion of which is formed by a collar 9 which can be moved along the shaft 5 but will be re- 60 volved therewith by a key 7. A spring 10 tends to move the collar 9 into engagement with the hub 8. On the collar 9 is loosely mounted a toothed or ratchet wheel 11, which is provided at one side with teeth 12 65 having sloping faces which are engaged by pins 13 of the collar 9. Normally the wheel 11 revolves with the collar, the latter engag- 70 ing the hub 8. If the wheel is to be checked by a pawl 20 in the manner herein- after described the pins 13, owing to the fact that the collar 9 is continually revolved by the shaft 4, slide along such sloping faces the teeth 12, whereby the collar 9 is shifted 75 towards the left (Fig. 1) and thereby is dis- engaged from the hub 8 of the driving pul- 80 ley 6, the spring 10 being tensioned. The collar 9 is held in disengaged position by a spring pawl 14 engaging a flange 15 of the collar 9. A handle 16 enables the pawl 14 to be released, so that the collar 9, constituting the movable clutch portion will be moved in engagement with the hub 8 constituting the fixed clutch portion by the spring 10.

The wheel 11 may be checked by a pawl 85 20 the rear arm 21 of which projects under a lug 22 of a lever 23. Said lug is cam shaped at its lower edge and provided there- at with two cam portions arranged in differ- 90 ent levels. The lever 23 is connected by a wire 24 or the like with the known thread guard (not shown). If a knitting thread breaks or exhausts the said thread guard by means of the wire 24 moves the lever 23 to- 95 wards the left, whereby the arm 21 is al- lowed to rise onto the higher cam portion of the lug 22 and thereby the pawl 20 engages the wheel 11. The latter will be checked and causes the clutch (8, 9) to be released as hereinbefore described.

In order to release said clutch also with each change of the pattern or after a predetermined number of cycles or revolutions of the shaft 5 a well known pattern chain 105 25 is provided. A known ratchet device 26 causes the pattern chain to be stepped at each rev- olution of the shaft 5, a retaining pawl 27 preventing the return movement. On the pattern chain 25 one or more buttons 28 may be secured, the positions of which corre- 110 spond to the points at which the pattern changes. Said button 28 acts upon a bell

crank lever 29 which in turn forces the lug 22 and the lever 23 to the left, so that the clutch (8, 9) will be released as hereinbefore described.

5 The driving shaft 5 transmits its motion as by means of chain wheels 30, 32 and a chain 31 to a shaft 33 mounted in a suitable bearing of a frame 34, which is mounted at the rear side of the knitting machine, of 10 which the angular support 35 of its carriage is illustrated, so that the latter may for the sake of discussion represent the carriage itself. The shaft 33 drives a chain gear which serves for reciprocating the carriage. 15 Said chain gear comprises a chain wheel 36 secured to the shaft 33, a chain wheel 37 secured to a shaft 38 which is mounted in the frame 34 and an endless chain 39. The chain 39 causes the carriage 35 of the knitting machine to be reciprocated in the same manner as has been effected hitherto by the well known crank mechanism.

Since the said chain gear has only reduced height, it may be mounted directly upon the 25 table supporting the entire knitting machine even when the carriage (35) performs the largest stroke. This would be impossible with crank mechanism because the crank would be too long.

30 The frame 34 carries guiding rods 40 and 41, on which a slide 42 may be reciprocated in a path being parallel to that of the carriage. The chain 39 traversing the slide is provided with a single pin 43 which engages 35 two vertical iron bars 44 slidably arranged and held in the slide. Said bars 44 move the slide and distribute the pull exerted by the chain so that jamming of the slide on the guiding rods 40, 41 will be prevented.

40 The slide or traveler 42 is provided with a drag bolt 45, which is guided in a vertical direction, a spring 46 tending to move the drag bolt 45 downwards. The bolt 45 being moved by the slide performs a stroke 45 which exceeds the stroke of the carriage in both directions. The head 47 of the angular support 35 firmly secured to the carriage is bevelled off at both sides as at 48 and is provided therebetween with a hole 49. The bolt 45 moving towards the head 47 rises along the sloped or bevelled portion 48 and then enters the hole 49, whereby the carriage will be dragged. Before the carriage arrives at the end of its stroke the bolt 45 will be lifted and drawn out of the hole 49 so that the carriage (35) comes at rest at the end of its stroke, whereas the slide 42 and bolt 45 continue their travel in the same direction and then return in the opposite direction.

60 The bolt 45 will be released in the following manner:

The frame 34 supports at its top two rails 50 and 51 between which the upper end of 65 the bolt 45 projects beyond such rails. In

the said end a transversal pin 52 is slidably mounted, so that it can be moved lengthwise or at right angle to the bolt. In one of the two positions the pin 52 slides only with one of its ends on one of the rails (for example 70 on 50) and in the other position only with the other end on the second rail (51). On the said rails 50, 51 brackets 53, 54 respectively are slidably and adjustably mounted, and each of said brackets carries a cam 55, 75 56 respectively and a curved spring plate 57, 58 respectively.

It will be assumed that the pin 52 of the bolt 45 runs upon the rail 50. If now said pin 52 rises to the summit of the cam 55 the bolt 45 will be raised and then being lifted clear of the hole the carriage (35) will be stopped. The bolt continues its travel in the same direction, whereby the end of the pin 52 will be forced inwards by the spring plate 57, so that said pin will be moved into the reversed position. In the latter position the pin 52 slides on the other rail 51 until it reaches the other cam 56 and then the described operation repeats at the 80 other side of the frame 1. As seen the distance between the two cams 55 and 56 corresponds to the stroke of the carriage, and by changing the positions of the brackets or cams 55, 56, i. e. by moving the brackets 85 along the rails or by reducing or increasing the distance between the two cams the chain gear may be adjusted according to any width of the knitting machine or to every stroke of the carriage.

In addition to the advantages above specified the chain gear allows that for changing the adjustment only the brackets 53, 54 are to be shifted along the rails 50, 51, whereupon said brackets will be secured in their new positions as by means of a set screw 59, but the operations of separating and connecting two elements (crank and connecting rod) as hitherto practised will be dispensed with.

110 What I claim is:

1. In a driving system a unitary driving mechanism for converting a hand driven straight knitting machine with rectilinearly movable carriage into a motor driven one, said mechanism comprising a driving shaft, a clutch between the driving shaft and the carriage of the knitting machine, means comprising an element which after a predetermined number of revolutions of the machine or in the event of a thread rupture will be checked, so as to cause the clutch to be thrown out of mesh, an endless chain actuated by the said driving shaft, means adapted to be reciprocated by the chain, means whereby the carriage of the knitting machine will be engaged by the said reciprocated means and disengaged therefrom.

2. In a driving system a unitary driving mechanism for converting a hand driven

straight knitting machine with rectilinearly movable carriage into a motor driven one, said mechanism comprising a driving shaft, a clutch between the driving shaft and the carriage of the knitting machine, an element for throwing said clutch out of mesh, after a predetermined number of revolutions of the machine, or if a knitting thread breaks an endless chain actuated by the said driving shaft, a traveller being moved by the chain and guides on rails parallel to the path of carriage of the machine, a drag bolt on the traveller which bolt is adapted to engage the carriage and means to disengage the drag bolt from the carriage.

3. In a driving system a unitary driving mechanism for converting a hand driven straight knitting machine with rectilinearly movable carriage into a motor driven one, said mechanism comprising a driving shaft, a clutch between the driving shaft and the carriage of the knitting machine, an element for throwing said clutch out of mesh, an endless chain actuated by the said driving shaft, a traveller being moved by the chain and guided on rails parallel to the path of carriage of the machine, a drag bolt in the traveller, which bolt is adapted to engage the carriage and having a transverse pin shiftably mounted in the bolt, a bracket at each end of the carriage stroke, each of said brackets being provided with a cam adapted to disengage the bolt from the carriage, and a curved plate adapted to shift the said pin longitudinally, said brackets being mounted adjustably on fixed rails for the purpose of enabling the stroke of the carriage to be ad-

justed according to any width of the knitting machine or to any width of the fabric to be manufactured.

4. In a knitting machine with a rectilinearly reciprocated carriage, a driving shaft, an endless chain, a head on the carriage provided with sloped faces at both its ends and with a hole therebetween, a traveller being reciprocated by the endless chain, a spring urged drag bolt on the traveller capable of entering the said hole, adjustable brackets each provided with a cam for lifting the said drag bolt so as to be clear of the said hole and with a curved plate, a transversal pin mounted in the drag bolt and capable of being shifted lengthwise by the said curved plate for the purpose of enabling the drag bolt to cooperate with the cam at the opposite side of the machine.

5. In a knitting machine with a rectilinearly reciprocated carriage, a driving shaft, an endless chain, a head on the carriage provided with sloped faces at both its ends and with a hole therebetween, a slide being reciprocated by the endless chain, a spring urged drag bolt on the slide capable to enter the said hole, adjustable brackets each provided with a cam for lifting the said drag bolt so as to be clear of the said hole and with a curved plate, a transversal pin mounted in the drag bolt and capable to be shifted lengthwise by the said curved plate for the purpose of enabling the drag bolt to cooperate with the cam at the opposite side of the machine.

In testimony whereof I affix my signature.
MAX EISENSCHIML.
